Primary Examiner — Melody N Brown(74) *Attorney, Agent, or Firm* — Haley Giuliano LLP(57) **CLAIM**

The ornamental design for a vehicle steering wheel horn pad as shown and described.

DESCRIPTION

FIG. 1 is a front elevational view of a vehicle steering wheel horn pad showing our new design;

FIG. 2 is a top plan view thereof;

FIG. 3 is a left-side elevational view thereof, the right side being a mirror image thereof;

FIG. 4 is a front and left side perspective view thereof; and, FIG. 5 is a rear and right side perspective view thereof.

The portions of the steering wheel shown in broken lines and the portions of the steering wheel shown in a de-emphasized faded out half-tone form surrounded by the broken lines and shown outside the solid line boundaries which represent and define the claimed design, are for environmental and illustrative purposes that form no part of the claimed design.
